CLAIM

The ornamental design for a computer, as shown and described.

DESCRIPTION

FIG. 1 is a front perspective view of a computer showing our new design;

FIG. 2 is a left side view thereof;

FIG. 3 is a right side view thereof;

FIG. 4 is a top view thereof;

FIG. 5 is a bottom view thereof; and,

FIG. 6 is a rear perspective view thereof.

The gray shading in FIGS. 1-6 represents a metallic-looking surface. It is understood that the ends of the gray shading along the sides of the computer in FIGS. 1-3 and 6 represent the bounds of the claimed design. The black screen border represents a periphery portion of the screen which is black. The broken lines are environmental only and form no part of the claimed design.
